TIMING MECHANISM

Filed Jan. 13, 1931

UNITED STATES PATENT OFFICE

FRANK A. BOOTH, OF EL SEGUNDO, CALIFORNIA

TIMING MECHANISM

Application filed January 13, 1931. Serial No. 508,429.

My invention relates to timing mechanisms, and more particularly to timing mechanisms for controlling electric circuits.

The objects of this invention are: first, to provide a timing mechanism whereby electric circuits may be closed and opened at predetermined times, and whereby circuits may be closed during predetermined periods, and also during predetermined successive periods; second, to provide a mechanism of this class which consists of a plurality of separate switches in connection with a clock or other timed mechanism so that anyone or a number of switches may be operated for closing portions of the circuit, which circuits are completed by the clock or other timing mechanism, the separate switches controlling the times at which the circuit is closed and opened for controlling the duration of a continuous period or successive periods during which the circuit is closed; third, to provide a mechanism of this class in which each of the separate of the multiplicity of switches controls the closing of the circuit for a short period, which period of closed circuit may be extended as desired by actuating as many of the adjacently positioned switches as necessary for extending the period for the duration desired; fourth, to provide a mechanism of this class in which such multiplicity of separate switches are arranged in cooperative relation with a clock dial so that the time may be readily determined at or during which the circuit is to be closed; fifth, to provide a mechanism of this class which, when used with the ordinary clock mechanism, will control the closing and opening of the circuit for a twelve hour period, and which permits the closing and opening of the circuit to be readily varied for each successive twelve hour period; sixth, to provide a mechanism of this class in which a multiplicity of circumferentially spaced apart and outwardly radiating contacts or conductors are arranged concentrically with respect to the axis of the dial and of the hand moving over the dial, and in which the circuit is completed by a uniformly rotating switch member carried by the spindle moving the hand, and in which the separate period controlling switches are

arranged in cooperative relation with the outwardly radiating contacts or conductors and in cooperative relation with the dial and hand so that the periods of closing and opening the periods may be readily determined; seventh, to provide a simple switch mechanism for connecting the time mechanism to the desired circuit, or for cutting out the time mechanism so that the electrical apparatus connected therewith may operate continuously, 55 or which switch may be operated to disconnect the electric current; and, eighth, to provide as a whole a novelly constructed timing and switch mechanism, and one which is relatively simple and economical of construction 60 and durable, one which is simple to operate, efficient, and which will not readily deteriorate or get out of order.

With these and other objects in view, as will appear hereinafter, I have devised a timing mechanism having certain novel features of construction, combination and arrangement of parts and portions, as will be herein-after described in detail and particularly set forth in the appended claims, reference being 70 had to the accompanying drawing and to the characters of reference thereon which form a part of this application in which:

Figure 1 is a partial front elevational and partial sectional view thereof; Fig. 2 is a fragmentary sectional view thereof taken through 2-2 of Fig. 1; Fig. 3 is a fragmentary sectional view thereof taken through 3-3 of Fig. 2; Fig. 4 is a fragmentary sectional view thereof taken through 4-4 of Fig. 3, showing the main switch; and, Fig. 5 is a dia- 80 grammatic view of the electric circuit controlled by the main switch.

Like characters refer to similar parts and portions throughout the views of the drawing.

The whole of the mechanism is enclosed in a casing 1 and supported on a base 2. The mechanism may assume the general appearance of a mantel clock and, when not used as a switch control mechanism, may be used as an ordinary time clock.

In the casing 1 may be mounted an ordinary clock mechanism. The principal features of this mechanism as far as it pertains 95 100

to the present embodiment of my invention, consists of an arbor or spindle 3 which is in tubular form, and which carries at its front or outer end an hour hand 4 and which is rotated at uniform speed by the usual spring mechanism of a clock, the spring and other mechanism being indicated generally by the numeral 5. The operating connection between the spindle 3 and the actuating mechanism consisting in this instance of a large gear 6 mounted on the spindle, a pinion 7 meshing with the gear 6 and mounted on a spindle 8, a large gear 9 mounted on the spindle 8 and meshing with a pinion 10 connected with the actuating mechanism. Through the tubular spindle 3 extends another spindle 11 which extends with its front end through the spindle 3 and carries the minute hand 12. This spindle 11 is operatively connected with the spindle 3 by a pinion 13 mounted on the spindle 11 and meshing with the gear 9. At the forward portion of the casing 1 and immediately behind the hour and minute hands is the usual 25 clock dial 14. The front end of the casing is enclosed by a glass plate 15 as in the usual clock construction.

Within the casing 1 and forming a part thereof is an annular insulating support 20 which is of annular construction and is positioned behind the dial and concentrically around the spindle 3. In this insulating support are mounted a multiplicity of resilient contacts 21 which consist preferably of flat 30 spring members radiating outwardly from the central portion of the support 20 and circumferentially spaced from each other. In the illustration, there are provided forty-eight of these contacts, dividing a twelve hour period into fifteen minute periods. The inner ends of the contacts 21 extend inwardly and slightly beyond the wall forming the annular central opening 20a of the support 20. The support 20 is provided with 40 an annular channel 20b outwardly from its central portion and between its front and rear sides. The contacts 21 extend with their outer ends into this annular channel.

In the support are mounted two annular conductors 22 and 23, the former being positioned backwardly from the contacts 21 at their inner ends but protruding inwardly into the annular opening 20a the same distance as the contacts 21. The other annular conductor 23 is located behind the contacts 21 and adjacent the outer or free ends thereof and is adapted to be engaged by the free ends of the contacts 21 when the same are forced backwardly by the switch members 24.

On the spindle 3 is mounted an insulating disc 25 to which is secured a resilient roller support 26, shown best in Fig. 1. The free end of the support 26 is bifurcated and on this bifurcated portion is mounted a roller 60 27 which is carried in a circular path by the

spindle 3 and is adapted successively to connect the adjacent contact 21 to the annular conductor 22 during the operation of the clock mechanism.

The switch members 24 are pivotally mounted on pins 28 which may consist of a continuous wire ring extending around the support, as shown in Fig. 1. These switch members extend radially from the support 20 and, in this instance, are adapted to be drawn forwardly for forcing the outer ends of the contacts 21 against the annular conductor 23. These switch members 24 are so arranged at the circumference of the casing and at the circumference of the dial that it may be determined without difficulty which switch member must be drawn forwardly in order to close the circuit at a particular time. It will be noted that the roller or switch member 27 is positioned directly behind or in alignment with the hour hand or so that the switch mechanism corresponds or coincides with the dial and the hour hand.

At the rear side of the insulating support 20 is provided a pair of terminals 31 and 32 to which the two ends of a circuit may be connected. The terminal 31 is connected directly to the annular conductor 22 by a conductor 33. At the upper portion of the insulating support is located the main switch, shown in Figs. 2, 3 and 4. This switch consists of pairs of spaced apart contacts 34 and 35 and 36 and 37, and a pivotally mounted switch member 38. At the inner end of the switch member 38 are provided spring expandible contacts 39. The contact 37 is connected directly to the annular conductor 23. The contact 35 is connected to the contact 36, that is to the terminal 32. As the switch member is shifted to the dotted line position as shown in Fig. 3, the terminal 32 is connected to the contact 37 and to the annular conductor 23, while the terminal 31 is connected to the annular conductor 22, thus placing the mechanism in condition for the time controlling. If the switch member 38 is shifted to the opposite angular position, the terminal 31 is connected to the conductor 35 and thence to the contact 36 and directly to the terminal 32, thus cutting out the timing mechanism. If the switch member is in the solid line position shown in Fig. 3, the circuit is broken.

Thus it will be seen that when the main switch is in the first position referred to, and when certain of the switches 24 are drawn forwardly, the circuit will be completed at the particular time corresponding with the switch member at the particular location 120 with respect to the dial when the hour hand reaches the corresponding position. Thus, if a number of adjacent switch members 24 are drawn forwardly, the circuit will be closed for a continuous period and will be 125 130

broken at the end of the period. The same is true for any group of switches 24.

It will be noted that my timing mechanism herein shown and described is particularly 5 advantageous and desirable in controlling the time and periods at and during which radio receiving sets are to be operated. The mechanism, however, is so constructed as to be applicable for many uses.

10 Though I have shown and described a particular construction, combination and arrangement of parts and portions, I do not wish to be limited to this particular construction, combination and arrangement, but desire 15 to include in the scope of my invention the construction, combination and arrangement substantially as set forth in the appended claims.

Having thus described my invention, what 20 I claim as new and desire to secure by Letters Patent is:

1. In a mechanism of the class described, a casing, a clock mechanism mounted in the casing and provided with a uniformly rotating 25 spindle, a plurality of contacts positioned around the spindle, spaced from the spindle and circumferentially from each other and radiating outwardly from the spindle, a switch member carried by the spindle and 30 adapted to engage each of the contacts during the rotation of the spindle, an annular distributing ring positioned to one side of and adjacent the outer ends of the contacts, and a plurality of switch members, one being provided 35 for each of the contacts at the outer ends thereof, each of the latter switch members being shiftably mounted on the casing in connection with each of the contacts, said latter switch members being so mounted as to 40 force the respective contacts into engagement with the distributing ring.

2. In a mechanism of the class described, a casing, a clock mechanism mounted in the casing and provided with a uniformly rotating 45 spindle, a plurality of contacts positioned around the spindle, spaced from the spindle and circumferentially from each other and radiating outwardly from the spindle, a switch member carried by the spindle and 50 engaging each of the contacts during the rotation of the spindle, an annular distributing ring positioned to one side of and adjacent the outer ends of the contacts, a plurality of switch members, one being provided for each 55 of the contacts at the outer ends thereof, each of the latter switch members being shiftably mounted on the casing in connection with each of the contacts, said latter switch members being so mounted as to force the respective 60 contacts into engagement with the distributing ring, a dial extending concentrically around the axis of the spindle, and a hand secured to the spindle and movable over the dial, the switch member carried by the spindle 65 being positioned in substantial alignment

with the hand, said other switch members being positioned adjacent the circumferential portion of the dial and cooperating therewith.

3. In a mechanism of the class described, a 70 casing, a clock mechanism in the casing, said clock mechanism being provided with a uniformly rotating spindle, an insulating support mounted in the casing around and coaxial with the spindle, a plurality of resilient contacts mounted in the support and radiating outwardly from the central portion thereof and spaced circumferentially from each other, a switch member carried by the spindle and adapted to engage the inner ends of all of said contacts, an annular distributing ring mounted in said support at one side of the resilient contacts, and a plurality of switch members mounted on the support for 80 separately forcing the desired contact in engagement with said annular distributing ring. 85

4. In a mechanism of the class described, a casing, a clock mechanism in the casing, said clock mechanism being provided with a uniformly rotating spindle, an insulating support mounted in the casing around and coaxial with the spindle, a plurality of resilient contacts mounted in the support and radiating outwardly from the central portion thereof and spaced circumferentially from each other, an annular conductor mounted on the support at the central portion thereof and spaced to one side of said contacts, a switch member resiliently and yieldably mounted on 90 said spindle and insulated therefrom connecting each of said contacts with said ring during the rotation of said spindle, a second annular conductor mounted on said support at one side of said contacts adjacent the outer ends thereof, a switch member in connection 95 with each of the outer ends of said contacts for forcing the same into engagement with the second annular conductor, and terminal posts connected to each of said annular conductors. 100

In testimony whereof, I have hereunto set 105 my hand at Los Angeles, California this 8th day of January 1931.
